UNITED STATES PATENT OFFICE.

FRANK BARR, OF THE UNITED STATES REVENUE MARINE.

SIGNAL-BUOY.

SPECIFICATION forming part of Letters Patent No. 237,361, dated February 8, 1881.

Application filed June 2, 1880. (No model.)

To all whom it may concern:

Be it known that I, FRANK BARR, a captain in the Revenue Marine of the United States, and a citizen of the United States, 5 domiciled therein, have invented certain new and useful Improvements in Automatic Signal-Buoys; and I do hereby declare that the following is a full, clear, and exact description of the invention, which will enable others skilled in the art to which it appertains to 10 make and use the same, reference being had to the accompanying drawings, which form a part of this specification, and in which—

Figure 1 is a view representing the method of 15 anchoring the buoy. Fig. 2 is a side elevation of the buoy detached from its anchorage. Fig. 3 is a plan or top view. Fig. 4 is a vertical central section, and Fig. 5 is a cross-section through line $x-x$ in Fig. 4.

20 Similar letters of reference indicate corresponding parts in all the figures.

My invention relates to that class of signal-buoys in which the signals are produced automatically by air compressed by the vertically- 25 reciprocating motion of the buoy, induced by the surface-waves, in a tube or cylinder which extends from the bottom of the buoy down into still water; and it consists, first, in the combination, with a buoy of this class, of an 30 air reservoir or chamber and an engine or other motor operated by compressed air and placed within said chamber; secondly, in the combination, with the buoy, its air-chamber, and its compressed-air motor or engine, 35 of a dynamo-electric engine and an electric lamp operated by the motor; thirdly, in the combination, in a single buoy, of a fog-signal and an electric beacon-light operated by compressed air independent of one another; and, 40 fourthly, in the detailed arrangement, construction, and combination of parts of my improved signal-buoy, substantially as herein-after fully set forth.

The fact that at a certain distance below the 45 surface of the ocean the water is always in a quiescent state, regardless of the agitation in the form of waves of its surface, has long ago been taken advantage of in the construction of automatically-operating signal-buoys in the 50 following manner: The buoy is provided with a downwardly-extending cylindrical tube of

such a length—say thirty feet, more or less—that it will reach below the depth to which water is agitated by the waves, and it follows that the water-level will remain constant at 55 the same point within the tube, the inclosed column of water not being affected by the waves. By lifting the buoy up and down as it rides upon the surface-waves the column of water within the tube will operate like a piston, or, rather, the inclosed column of water will remain stationary while the enveloping-tube works up and down around it; and by providing the upper closed part of the tube with a suitable air-inlet having an inwardly-opening 60 check-valve, air will be fed into the tube every time the buoy rises on the crest of a wave, and as it descends into the trough of the wave the air-inlet is closed by the pressure from within, and the compressed air contained in 65 the upper part of the tube or cylinder is forced out through a whistle or other sounding apparatus, which forms the air outlet or exit from the tube or compressed-air chamber. Thus we have an automatic signal-buoy signaling 70 by whistling; but by my invention an additional means of signaling by light is provided, the advantage of which is too apparent to require demonstration.

In the drawings hereto attached, A is the 80 upper air-tight chamber or body of the buoy, which is placed upon a boat or pram, B, having a flat deck, b.

C is the tube or cylinder, which extends from the bottom of the upper chamber or body of 85 the buoy down through the lower part or boat B, and should be of such a length as to reach down into the still-water region below the surface or region of agitation. A pipe, D, reaches from the upper closed end of tube C up through 90 the air-chamber, passing through its top, and is provided with a back-pressure valve or any other suitably-constructed valve, d, through which air is fed into the tube or cylinder C at every rising of the boat with its superimposed 95 chamber. As the boat descends into the trough of the sea valve d is closed as to the inlet of pipe D, but opens into the chamber A, thus allowing the air to escape at d' out into said chamber or reservoir, which is inclosed air-tight on all sides. Thus it will be observed 100 that the upper part or body of the buoy forms

a storage chamber or reservoir for compressed air, which is fed into it from the air-chamber in pipe C above the water-line, and this is utilized to drive an engine, E, or other motor of suitable construction and capable of being operated by compressed air.

In the drawings I have represented an oscillating-cylinder engine, which, as usual in this class of engines, feeds through a hollow trunnion and exhausts through a pipe, e, which extends up through the top of the buoy and is provided with a suitably-constructed cap to prevent ingress of water in rough weather. This engine or motor, which should be provided with a suitably-constructed governor (by preference so arranged that it may be adjusted from the outside of the buoy without opening said buoy) for the purpose of regulating and controlling its speed, runs a dynamo-electric engine, F, which supplies the current through wires m n for an electric lamp or lantern, G, placed upon the top of the buoy.

If it is desired to use an oil lamp or lantern—a Fresnel light, for example—instead of the electric light, the engine E may be employed to pump the oil from the hold in the lower part of the buoy—i. e., the boat B, which is capable of containing a large supply, lasting several months—up into the lamp, which should have an asbestos or other indestructible wick, and also an overflow-pipe for conveying the surplus of oil back into the reservoir in the boat. Or the compressed-air motor, constructed and arranged as described, may be employed to run a gas-engine, or, in fact, any other kind of engine or apparatus for producing a light adapted for the circumstances and conditions of the case. The buoy itself is of sufficient size to serve as a "day-mark," and we have seen how it may also, by my invention, be made to serve the purposes of a beacon or night-signal. By the attachment of a whistle, siren, or other sounding apparatus, it may be made to serve as a fog-signal also, in a very simple and efficient manner, and altogether independent of the apparatus for operating the light-signal, in the following manner:

The downwardly-extending tube or cylinder C is divided by a longitudinal diaphragm, e, Figs. 4 and 5, into two compartments, e f, the larger one of which, e, forms the lower compressed-air chamber with its stationary column of water, furnishing the power to run the motor in the upper air-chamber, A, in the manner described. The smaller compartment, f, is continued up through the said chamber A by a pipe, H, which, in like manner as pipe D, is fitted with a back-pressure valve and provided with a whistle or other sounding apparatus, I, at its upper end, which projects out through the top of the buoy. I prefer to enlarge that part of pipe H which passes through chamber A, as shown in Fig. 4 of the drawings, by which means an air chamber or reservoir is formed of sufficient capacity to hold a suitable quantity of compressed air to operate the whistle. As the buoy rises on the crest of

a wave air enters pipe H and the compartment f through the back-pressure valve, which is closed as the buoy descends, but opens the inlet to the whistle, which is sounded by the forcing of the compressed air through it.

The lower part of the buoy, consisting of the boat or pram B, is of the construction and shape shown in the drawings, and is provided with a treble keel, or rather a keel composed of a middle part or keel proper, K, which extends from the peak or stem of the boat abaft to tube C, against which its rear end abuts, and two parallel side wings, L L, reaching from about the middle of tube C back to the stern of the boat. By this construction and arrangement of the boat with its keels I secure steadiness of motion of the buoy, causing it to stand vertical in any sea.

The buoy is connected by a chain or steel rope, M, of suitable length, to a nun-buoy, N, which is anchored by a chain cable, O, in mid-ocean, or wherever else it may be desired to place the buoy. This arrangement gives a more free vertical motion to the buoy A B than if it has to drag the heavy anchoring-cable which is supported by the intermediate nun-buoy, N. Besides, chafing of the downwardly-extending tube against the anchoring-cable is thereby absolutely prevented.

Having thus described my invention, I claim and desire to secure by Letters Patent of the United States—

1. A signal-buoy provided with an air reservoir or chamber, means for feeding and compressing air into said reservoir or chamber by the motion of the buoy, and an engine or motor placed within said reservoir and operated by compressed air, substantially as set forth.

2. The combination, with a signal-buoy having a water-tube extending downwardly below the body of the buoy, of a compressed-air chamber or reservoir and an engine or motor adapted to be operated by compressed air, substantially as set forth.

3. In combination, a signal-buoy having a downwardly-extending water-tube with an air reservoir or chamber above the water-level, an upper air-chamber fed from said lower chamber, an engine placed within said upper reservoir or chamber and adapted to be operated by compressed air, and an exhaust leading from the engine to the outside of the air-chamber, substantially as set forth.

4. In a signal-buoy, a downwardly-extending water-tube divided by a longitudinal partition or diaphragm into two compartments, adapted to supply two or more separate chambers or reservoirs, A H, in the buoy with compressed air, independent of one another, substantially as set forth.

5. In a signal-buoy an inclosed air-chamber, means for feeding and compressing air into said chamber by the motion of the buoy, an electric lamp or lantern placed outside of said chamber, wires or conductors connecting said lamp or lantern with a dynamo-electric engine arranged inside of the chamber, and an air-

engine or motor placed within said air-chamber and connected by suitable gearing or belting to the electric engine, all constructed, combined, and operating substantially as and for the purpose herein shown and specified.

6. A signal-buoy having an upper air-chamber, a boat or float supporting said air-chamber, an open-bottomed tube or cylinder extending downwardly from the air-chamber, and a pipe or tube leading from the tube or cylinder through the air-chamber to the outer air, said pipe having a back-pressure or similar valve adapted to alternately open the pipe to the outer air but close it to the air-chamber, and vice versa, substantially as set forth.

7. A signal-buoy having an air-chamber, a boat or float supporting said air-chamber, an open-bottomed tube or cylinder extending downwardly from the air-chamber and divided by a longitudinal diaphragm into two compartments, a pipe leading from one of said compartments to the outer air, and a pipe leading

from the other of said compartments to the outer air, substantially as and for the purpose herein shown and set forth.

8. The boat-shaped buoy float or support B, having downwardly-extending water-tube C, a middle keel, K, extending from the stem toward and abutting against said water-tube, and two side keels or wings, L L, extending from the middle abaft to the stern of the boat, substantially as set forth.

9. The signal-buoy A B, with downwardly-extending water-tube C and treble keel K L L, attached to an anchoring-cable, M, below the water-line by its middle keel, K, substantially as set forth.

In testimony that I claim the foregoing as my own I have hereto affixed my signature in presence of two witnesses.

FRANK BARR.
